UNITED STATES PATENT OFFICE

110,128

DESIGN FOR A BARRETTE

Daniel D. Whyte and Stephen F. Kayn, New York, N. Y., assignors to Injection Moulding Corporation, New York, N. Y.

Application October 8, 1937, Serial No. 72,084

Term of patent 3½ years

To all whom it may concern:

Be it known that we, Daniel D. Whyte, a citizen of the United States, residing at No. 2 St. Paul's Place, city of New York, in the county of Kings, and State of New York, and Stephen F. Kayn, a citizen of the United States, residing at No. 35 East 9th Street, city of New York, county of New York, and State of New York, have invented a new, original and ornamental Design for a Barrette, of which the following is

a specification, reference being had to the accompanying drawing, forming part thereof, in which

Figure 1 is a front elevational view of the barrette showing our new design.

Figure 2 is a rear elevational view thereof.

Figure 3 is a plan view thereof.

We claim:

The ornamental design for a barrette, as shown.

STEPHEN F. KAYN.

DANIEL D. WHYTE,
